United States Patent

Des. 237,930
Patented Dec. 9, 1975

237,930

CHILD'S WORKBENCH

Darwin L. Demmer, 379 Perkinswood SE.,
Warren, Ohio 44483

Filed June 13, 1973, Ser. No. 369,443

Term of patent 14 years

Int. Cl. D6—03

U.S. Cl. D6—179

FIG. 2.

FIG. 1.

FIG. 4.

FIG. 3.

FIG. 1 is a perspective view showing my new design for a child's workbench;

FIG. 2 is a fragmentary perspective view looking from the right end of FIG. 1, drawn to a reduced scale;

FIG. 3 is an end view looking from the left end of FIG. 1; and

FIG. 4 is a view looking from the front of FIG. 1.

I claim:

The ornamental design for a child's workbench, substantially as shown.
